UNITED STATES PATENT OFFICE

ARTHUR DUGREY, OF DETROIT, MICHIGAN, ASSIGNOR TO HOLLEY BROTHERS COMPANY, OF DETROIT, MICHIGAN, A CORPORATION OF MICHIGAN.

CARBURETER.

1,186,976.

Specification of Letters Patent. Patented June 13, 1916.

Application filed March 3, 1914. Serial No. 822,120.

To all whom it may concern:

Be it known that I, ARTHUR DUGREY, a citizen of the United States of America, residing at Detroit, in the county of Wayne and State of Michigan, have invented certain new and useful Improvements in Carbureters, of which the following is a specification, reference being had therein to the accompanying drawings.

The invention relates to carbureters of that type in which a separate passage is provided for the commingled air and fuel when the engine is idling, from the main passage used when the engine is working under load.

It is the object of the present invention to obtain a construction which will operate more satisfactorily under variable conditions and in which adjustment is effected by the setting of a single valve.

It is a further object to utilize a differential pressure drop for discharging the liquid fuel into the main and auxiliary mixing passages.

In the drawings: Figure 1 is a longitudinal central section through the carbureter; and Fig. 2 is a diagram showing a modified construction and also the differential pressure drop in different portions of the mixing chamber and under varying velocities.

A is the carbureter casing which is provided with an annular float chamber B containing the float C and a central discharge nozzle D controlled by the needle valve E.

F is an air inlet passage to the casing and G is the main mixing chamber arranged within the inlet chamber F and concentric with the discharge nozzle D.

H is a throttle valve and I is the auxiliary passage for the fuel above the throttle H when the engine is running idle.

To secure a more thorough commingling of the fuel and air and also effect adjustment by a single valve, the discharge nozzle for the fuel is of the following construction: I' is the restricted passage which is directly controlled by the needle valve E and which terminates at a point below the normal level J of the liquid within the float chamber. K is a cup at the upper end of the passage I' which rises to a point above the level J. L is an extension of the nozzle which is arranged within the cup K, its lower end being supported from the bottom of said cup and its upper end rising to a

point above the level J and within the mixing chamber G. As specifically shown in Fig. 1, the tube L is formed in two sections L' and L², the former being a restricted nozzle secured in the spider M extending across the cup K. The section L² is of larger diameter and is provided with a series of small openings L³ at its lower end which are arranged slightly below the upper end of the nozzle L' and also below the top of the cup K. The tube I which forms the auxiliary passage for the fuel to the point above the throttle H has its lower end extended downward into the cup K, where it is sealed by the liquid therein when at the normal level J. Thus in initial operation, where the throttle H is closed, the suction produced by cranking the engine will cause the lifting of the liquid fuel in the cup K through the tube I and the discharge of the same into the passage above the throttle H, thereby priming the engine. The fuel will continue to pass through this tube when the engine is idling, the throttle H being closed, but whenever the throttle is open, the velocity of the air current passing through the chamber G will produce a pressure thereby at the upper end of the nozzle section L², which will discharge the liquid from the cup K through said nozzle into the main air current. This action will unseal the lower end of the tube I, preventing further passage of the liquid thereinto, and will also permit the air from the inlet F to pass downward in the cup and into the lower end of the nozzle L, where it is commingled with the stream of liquid discharged through the passage I'.

With the construction as above described, whenever it is necessary to adjust the carbureter, the opening or closing of the valve E will effect this adjustment which will control both the main and the auxiliary commingling devices. Furthermore, when the carbureter is operating under variable velocities of air current there will be an increase and decrease of pressure drop at both the discharge end of the nozzle L and also at the discharge end of the passage I', but the ratio of variation is not the same. This is indicated in the diagram, Fig. 2, in which the curves O O', etc., indicate the relative variation in pressure drop at different points in the mixing chamber, which is in projection therewith.

The purpose of forming the tube L^2 of greater diameter than the nozzle L' and of also providing the inlet apertures L^3 , is to accelerate the action. Thus, were the nozzle 5 L to extend without interruption from the cup to the point where it terminates in the mixing chamber, an appreciable time interval would be required in elevating the liquid fuel through this nozzle before it would be 10 mixed with the air. On the other hand, with the construction as shown, the pressure drop at the upper end of the section L^2 will be transferred therethrough to a point immediately above the nozzle section L' , 15 which will quickly lift the oil therein, while the air entering through the ports L^3 will be commingled with the oil.

It will be noted that the form of the 20 passage within the carbureter casing is that of a Venturi tube, this tube being doubled back upon itself.

What I claim as my invention is:—

1. In a carbureter, the combination with a 25 casing having a Venturi tube providing a commingling passage, of an interrupted open ended nozzle for the discharge of the liquid fuel into said passage having restricted communication at a plurality of separate points along the longitudinal axis 30 thereof with said Venturi tube only.

2. In a carbureter, the combination with a 35 casing having a Venturi tube providing a commingling passage, of an interrupted nozzle for discharging the liquid fuel into said passage, having its outer end unrestricted and located above the normal level of the liquid, and the interruptions located below said level at different depths and adapted to restrictedly communicate only 40 with said Venturi tube.

3. In a carbureter, the combination with a 45 casing having a Venturi tube providing a commingling passage, of an interrupted nozzle for discharging liquid fuel into said passage, the upper end of said nozzle being unrestricted and located above the normal level of the liquid and at a point of greater pressure drop, and the interruption being below said level and adapted to restrictedly 50 communicate with said Venturi tube only at separate points of less pressure drop, and a cup surrounding the interruption in said nozzle and rising to normal level of the liquid.

55 4. In a carbureter, the combination with a casing having a Venturi tube providing a commingling passage, of a throttle valve for said passage, an interrupted nozzle for discharging liquid into said passage below 60 said throttle valve, the upper end of said nozzle being open and above the normal level of the liquid and the interruption be-

ing below said level and adapted to restrictedly communicate with said Venturi tube only, a cup surrounding said interruption and rising to the hydrostatic level, and an auxiliary discharge conduit having its lower end extending into said cup below said level and its upper end discharging above said throttle valve. 70

5. In a carbureter, the combination with a 75 casing having a commingling passage adapted to produce a variable pressure drop in different portions thereof, of a nozzle for discharging the liquid fuel into said passage comprising a restricted member arranged at a point where there is less than the maximum pressure drop, said restricted member having restricted communication with said passage only, and an open ended tubular 80 member extending from a point of greater pressure drop into proximity to the discharge end of said restricted member, said tubular member transferring substantially said greater pressure drop. 85

6. In a carbureter, the combination with a 90 casing having a Venturi tube providing a commingling passage, of a nozzle for discharging the liquid fuel, comprising a restricted portion and an unrestricted portion of greater diameter than said restricted portion extending from a point in said commingling chamber having a greater pressure drop to the upper end of said restricted portion and provided with laterally restricted air inlet portions adjacent to said restricted portion adapted to communicate with said Venturi tube only. 95

7. In a carbureter, the combination with a 100 casing having a commingling passage, of a nozzle for discharging the liquid fuel into said passage, and means for substantially transferring the pressure drop occurring at a higher point in said commingling passage to a point adjacent to the lower end of said nozzle, said transfer being substantially independent of the flow through said passage.

8. In a carbureter, the combination of a 105 casing having a Venturi tube providing a commingling passage, of an interrupted nozzle having a restricted nozzle and a nozzle tube of larger diameter than said restricted nozzle, said nozzle tube having an unrestricted upper end terminating at a point of greater pressure drop within said Venturi tube, and a lower end adapted to communicate with a point of a lower pressure drop within said Venturi tube only. 110

In testimony whereof I affix my signature in presence of two witnesses.

ARTHUR DUGREY.
